Primary Examiner — Leanne Was-Englehart*(74) Attorney, Agent, or Firm* — Michael Best & Friedrich LLP(57) **CLAIM**

We claim the ornamental design for a light, as shown and described.

DESCRIPTION

FIG. 1 is a first perspective view of a light according to an embodiment of the invention.

FIG. 2 is a second perspective view of the light of FIG. 1.

FIG. 3 is a third perspective view of the light of FIG. 1.

FIG. 4 is a side view of the light of FIG. 1.

FIG. 5 is a top view of the light of FIG. 1; and,

FIG. 6 is a bottom view of the light of FIG. 1.

Elements in the drawing identified with "transparent material" surface shading can be transparent or opaque. The broken lines show portions of the article which form no part of the claimed design.
